UNITED STATES PATENT OFFICE.

EARL L. GILMORE, OF SAN FRANCISCO, CALIFORNIA, ASSIGNOR TO VITASLIDE COMPANY, OF SAN FRANCISCO, CALIFORNIA, A FIRM.

PROJECTOR.

1,345,084.

Specification of Letters Patent. Patented June 29, 1920.

Application filed November 6, 1918. Serial No. 262,261.

To all whom it may concern:

Be it known that I, EARL L. GILMORE, a citizen of the United States, residing in the city and county of San Francisco, State of California, have invented a new and useful Improvement in Projectors, of which the following is a specification.

My invention relates to improvements in projectors and the like wherein a weight 10 operates in conjunction with a magnet to continuously rotate a transparent image carrying element between the objective and the condensing lenses of a projector.

The primary object of the present invention is to provide a simple, cheap and effective mechanism for operating a projector and slide therefor slowly and continuously.

A further object of the present invention is to provide an improved projector operated by gravity, said gravity operating means also operating a magnetic mechanism at regular intervals for resetting the gravity operating means.

It is also an object of the present invention to provide an improved mechanism for making and breaking an electrical contact magnetically with such rapidity as to reduce sparking and consequent erosion of contacts to a minimum, thereby eliminating 30 the necessity for expensive contact points and consequently reducing the cost of producing the projector.

A still further object of the present invention is to provide means for maintaining 35 a contact to produce a continued flow of electrical energy through a solenoid during the full stroke of the core thereof whereby said core may operate to reset a gravity operated device which in turn operates to rotate a transparent image carrying element.

I accomplish these and several other objects by means of the device disclosed in the drawings forming a part of the present specification wherein like characters of reference are used to designate similar parts throughout the said specification and drawings, and in which—

Figure 1 is a side elevation of my improved projector;

50 Fig. 2 is a view taken on line 2—2 of Fig. 1 in the direction indicated;

Fig. 3 is an enlarged broken sectional view of the operating mechanism;

Fig. 4 is a partly broken elevation of the 55 contacting device;

Fig. 5 is a plan view of the contacting device; and

Fig. 6 is a vertical sectional view of the heat operated means for breaking the current for operating the operating mechanism. 60

Referring to the drawings the numeral 1 is used to designate a suitable frame upon which is mounted a lantern housing 2 having the usual lamp therein as indicated in dotted lines in Fig. 1 of the drawings. 65

The lantern 2 is provided with a suitable condensing lens 4 with which is alined an objective lens within a barrel 6 slidably mounted upon a plate 7 secured to the top of a suitable support 8 secured to the 70 frame 1.

A transparent image carrying disk 9 is rotatably mounted upon the upper end of a suitable standard 11 and operatively connected to a frictional ratchet 12 arranged 75 concentric therewith.

The ratchet 12 is provided with diametrically opposed arms 14 and 14' and to the outer end of the arm 14 is suspended, by means of a suitable connecting link 16, a 80 stem 17 having a weight 18 and the core 19 of a solenoid magnet 21 secured thereto.

A sleeve 22 is slidably mounted upon the stem 17 and is provided with a magnetically influenced steel collar 23 having a pin 85 24 to which is attached a spring contact closing member 25, the purpose and operation of which will hereinafter be more fully described.

An insulating collar 26 is mounted in the 90 central aperture of the solenoid 21 and a spring 27 is interposed between the said collar 26 and the collar 23 on the sleeve 22.

The sleeve 22 is insulated from the stem 17 by means of an inner tube 28 of suitable 95 insulating material.

Mounted within an insulating block 31 upon the solenoid 21 are two parallel contacts 32 and 32' which are arranged within the downward path of the contact closing 100 member 25 carried by the collar 23 on the sleeve 22.

A circuit breaking device comprises an inverted cup 33 of suitable insulating material containing mercury 34 held in position by paraffin or similar substance as shown at 36. Extending through the top of the cup 33 and into the mercury 34 are two binding posts 37 and 37'. The cup 33 is also mounted upon the solenoid 21, the 110

purpose and operation of which cup will hereinafter be more fully described.

A wire leads from the source of electrical energy not shown, to one of the binding 5 posts 37, to conduct a current through the mercury 34 to the other binding post 37' from which a connection leads to one side of the solenoid 21, and from the other side of the solenoid 21 a wire leads to one of the 10 contacts 32. The remaining contact 32' is connected to the other side from the source of electrical energy.

From the arm 14' of the ratchet 12 is suspended, by means of a connecting link 38, the stem 39 of a piston 41 apertured as at 15 42. The apertures 42 are normally closed by means of a weight-valve 43. The piston 41 is slidably mounted within a suitable cylinder 44 connected to the frame 1 and is 20 filled with a fluid, preferably kerosene.

In operation the weight 18 and core 19 of the solenoid are actuated by gravity to operate the frictional ratchet 12 and rotate the disk 9. The speed of the disk 9 is normally 25 retarded by the fluid 45 which resists the movement of the piston 41 within the cylinder 44.

There is sufficient clearance between the piston 41 and the cylinder 44 to permit the 30 passage of only a small portion of fluid, therefore the movement of the piston is retarded and the disk 9 moves very slowly.

As the weight 18 and the core 19 of the solenoid 21 move downwardly the lower end 35 of the weight 18 engages the collar 23 and moves the contact closing member 25 downwardly until said member 25 makes contact with the contacts 32 and 32' thereby closing a circuit through the solenoid 21 and energizing the same. The energizing of the solenoid 21 immediately attracts the steel 40 collar 23 and thereby actuates the same to move the contacts 25 with greater pressure against the pins 32 and 32', thereby insuring a proper contact between said contact member 25 and pins 32 and 32' to prevent arcing and consequent erosion of said contact 25 and pins.

The resiliency of the spring contact member 25 holds said contact in position, thereby 50 insuring a flow of the full strength of the current through the solenoid 21 until released by the upward movement of the solenoid core 19 in a manner hereinafter more fully described. As the weight 18 is moved upward and as the ratchet 12 is reversed the ratchet is automatically released from the disk 9 in a manner well known in the state of the art, and the piston 41 is moved downwardly against the fluid 45 and the resulting pressure raises the weight valve 43 from the apertures 42 to permit the passage of fluid through said apertures 42 thereby permitting a quick return movement of said piston 60 41 and consequently a rapid resetting at the 65

gravity operated mechanism comprising the weight 18 and the core 19 of the solenoid 21.

As the core 19 moves upwardly an insulating washer 46 on the upper end thereof strikes the bottom of the insulating tube 28 70 and thereby moves the contact closing member 25 out of contact with the contacts 32 and 32' and the spring 27 also operates to move said contact member 25 away from said contacts 32 and 32'.

If for any reason the member 25 should remain in contact with the contacts 32, 32' the resulting heat generated within the solenoid 21 will melt the paraffin 36 within the cup 33 and thereby permit the lowering of 80 the mercury 34 to break electrical connection between the binding posts 37 and 37' and thereby deenergize the solenoid 21 and prevent the same from burning out.

The rapid release or breaking of contact 85 between the member 25 and the contacts 32 and 32' prevents arcing and erosion of the member 25.

It is evident that each time the weight 18 is lowered to make contact between the 90 member 25 and the contacts 32 and 32' the solenoid 21 will be energized to raise the weight 18 and reset the gravity operated mechanism as well as the fluid retarding means.

From the foregoing it is obvious that the projector may be operated by gravity and said gravity operated mechanism is reset at regular intervals by the energizing of the solenoid.

Therefore a very small quantity of current only will be required at great intervals to keep the disk 9 in motion.

In projectors formerly constructed, the movement of the image-carrying disk is intermittent, and the image is thus held before the spectator a considerable length of time, without any indication that subsequent images are to be projected. By this arrangement the spectator's attention is diverted so that he may lose interest in the images that are to follow. On the contrary, it is seen that my projector is so constructed that an image produced thereby always moves slowly and continuously, thus presenting before the spectator one of a series of constantly changing pictures, in which a subsequent picture comes into view before the preceding picture has disappeared, and thus holding the attention and the interest 100 of the spectator to the utmost.

Having thus described my invention, what I claim as new and desire to secure by Letters Patent is—

1. A projector comprising a lantern; an objective lens alined with the lantern; a transparent image carrying element arranged between the lantern and the lens; and gravity operated means for moving the image carrying element between the lantern 125 and gravity operated means for moving the image carrying element between the lantern 130

and the lens, means for instantly resetting said gravity operated means to effect a substantially continuous movement.

2. A magnetic projector comprising a lantern having a suitable condensing lens therein; an objective lens alined with the condensing lens and lantern; a transparent image carrying element rotatably mounted between the condensing and objective lenses; gravity operated means for rotating the image carrying element; and magnetic means operatively connected to the gravity operated means for instantly resetting the same at regular intervals.

15 3. A magnetic projector comprising a lantern having a suitable condensing lens therein; an objective lens alined with the condensing lens and lantern; a transparent image carrying element rotatably mounted between the condensing and objective lenses; gravity operated means for continuously rotating the image carrying element; and magnetically operated means operatively connected to and actuated by the gravity operated means for instantly resetting said gravity operated means at regular intervals to effect a substantially continuous rotation.

4. A magnetic projector comprising a lantern having a suitable condensing lens; an objective lens alined with the condensing lens; a transparent image carrying element rotatably mounted between the lenses; a gravity actuated means for rotating the image carrying element; a solenoid; a core slidably mounted within the solenoid and operatively connected to the gravity actuated means; and a contact closing element slidably mounted upon the gravity actuated means and adapted to be actuated by the said means to close a circuit through the solenoid to actuate the core thereof to reset the gravity operated means and to retain the contact closing means in operative position until released by the movement of the core.

45 5. A magnetic projector comprising a lantern having a suitable condensing lens therein; an objective lens alined with the condensing lens and in spaced relation thereto; a circular transparent image carrying element rotatably mounted with one side thereof between the lenses; gravity operated means operatively connected to the image carrying element and adapted to rotate said element; retarding means operatively connected to the gravity operated means to control the speed of the same; and magnetically operated means for instantly resetting the gravity operated means and the retarding means connected thereto at regular intervals.

6. A magnetic projector comprising a lantern having a suitable condensing lens therein; an objective lens alined with the condensing lens and in spaced relation

thereto; a circular transparent image carrying element rotatably mounted with one side thereof between the lenses; gravity operated means operatively connected to the image carrying element and adapted to continuously rotate said element; retarding means operatively connected to the gravity operated means to control the speed of the same; magnetically operated means for instantly resetting the gravity operated means and the retarding means connected thereto at regular intervals; a source of electrical energy; and means operated by the gravity operated means for connecting the source of electrical energy with the magnetically operated means at regular intervals to reset the gravity operated means and the retarding means therefor.

7. A magnetic projector comprising a lantern having a suitable condensing lens; an objective lens alined with the condensing lens; a transparent image carrying disk rotatably mounted between the lenses; a frictional ratchet operatively connected to the disk; gravity operated means operatively connected to the ratchet and adapted to rotate the disk continuously; retarding means operatively connected to the gravity operated means to control the speed of said means; and magnetically operated means actuated by the gravity operated means at regular intervals for instantly resetting said means and the retarding means.

8. A magnetic projector comprising a lantern having a suitable condensing lens; an objective lens alined with the condensing lens; a transparent image carrying element rotatably mounted between the lenses; gravity operated means operatively connected to the transparent element and adapted to normally rotate the same continuously between the lenses; a fluid retarding means operatively connected to the gravity operated means to control the speed thereof; and magnetically operated means actuated by the gravity operated means at regular intervals to reset the gravity operated means and the fluid retarding means therefor.

9. A magnetic projector comprising a lantern having a suitable condensing lens; an objective lens alined with the condensing lens; a transparent image carrying disk rotatably mounted between the lenses; a frictional ratchet operatively connected to the disk; a gravity operated means operatively connected to the frictional ratchet to rotate the disk; a fluid retarding means operatively connected to the frictional ratchet to retard the speed of the disk; a solenoid magnet arranged beneath the gravity operated means; a source of electrical energy; means operated by the gravity operated means for connecting the source of electrical energy with the solenoid at regular intervals to instantly reset the gravity operated means and

the fluid retarding means therefor whereby the disk may be continuously rotated.

10. A magnetic projector comprising a lantern having a suitable condensing lens therein; an objective lens alined with the condensing lens; a transparent image carrying disk rotatably mounted within one side thereof between the lenses; a frictional ratchet operatively connected with the disk; 10 a weight operatively connected to the ratchet and adapted to rotate the disk continuously; a fluid retarding mechanism operatively connected to the ratchet to retard the speed thereof; a solenoid magnet arranged below the weight; a source of electrical energy; and means operated by the weight at regular intervals to connect the source of electrical energy with and thereby energize the solenoid to raise and thereby 20 instantly reset the weight and the fluid retarding means.

11. A magnetic projector comprising a lantern having a suitable condensing lens therein; an objective lens alined with the condensing lens; a transparent image carrying disk rotatably mounted between the lenses; a friction ratchet operatively connected to the disk and arranged to rotate the

same when turned in one direction; a solenoid magnet; a source of electrical energy; 30 a pair of contacts one of which is connected to the solenoid and the other to the electrical source of energy; a solenoid core slidably mounted within the solenoid and connected to the ratchet; a weight connected to the core and ratchet whereby said ratchet may be operated by the combined weight of the said core and weight to rotate the disk; a fluid retarding means operatively connected to the weight; a sleeve slidably connected to the core and weight and insulated therefrom; a suitable spring supporting the sleeve; a contact closing element mounted upon the sleeve and arranged to pass between and connect with the contacts when 40 the weight and core are lowered by gravity and thereby energize the solenoid to raise the core thereof and the weight to reset the said weight and the fluid retarding means and to remove the contact closing element 50 from between the contacts and thereby de-energize the solenoid.

In witness whereof I hereunto set my signature.

EARL L. GILMORE.
